DISPLAY TRAY

Eugen F. Prestinari, Short Hills, N. J., assignor to
Gemex Company, Union, N. J., a corporation
of New Jersey

Application December 21, 1950, Serial No. 202,027

5 Claims. (Cl. 206—75)

1

This invention relates to display trays, and more particularly to display trays for watch bands, bracelets or the like which are sold mounted on rectangular paper cards.

The object of the invention is the provision of a display tray for holding cards on which are mounted watch bands, bracelets or the like in neat array with the tray of lightweight construction so that it may be easily handled.

In general, a display tray of this invention comprises an open rectangular frame having a width corresponding to the length of the cards which it is to hold. The frame has an integral inwardly directed flange forming a downwardly facing shoulder. At each of two opposite sides of the frame is a series of narrow partitions formed integral with the frame projecting down from the flanges and spaced at intervals slightly greater than the width of the cards, each partition at one side being opposed to a partition at the other side. A rectangular bottom corresponding in size to the opening in the frame is fitted in the frame abutting the lower edges of the partitions. The bottom is held in place in the frame by retainers formed integral with the frame extending under the margins of the bottom. This arrangement is such that the downwardly facing shoulder of the flanges, the partitions, and the bottom define two series of opposed pockets at the two opposite sides of the frame adapted to receive the ends of the cards to hold the cards in neat array. Other features will be in part apparent and in part pointed out hereinafter.

The invention accordingly comprises the elements and combinations of elements, features of construction, and arrangements of parts which will be exemplified in the structure hereinafter described and the scope of the application of which will be indicated in the following claims.

In the accompanying drawing, in which one of various possible embodiments of the invention is illustrated;

Fig. 1 is a plan view of a display tray of this invention;

Fig. 2 is an enlarged section on line 2—2 of Fig. 1, with parts broken away;

Fig. 3 is an enlarged section on line 3—3 of Fig. 1, with parts broken away; and,

Fig. 4 is a fragmentary bottom plan view of the tray shown in Fig. 1, with a bottom panel and backing strip removed.

Similar reference characters indicate corresponding parts throughout the several views of the drawing.

Referring to the drawing, the display tray of this invention is shown to comprise an open rectangular frame generally designated 1 having

2

end members 3, and side members 5. The tray is approximately twice the length of the cards to be displayed therein, and has a central dividing member 7 extending from one side member 5, to the other. Within the frame on opposite sides of the central member 7 are two lightweight bottom panels 9. In a preferred form, the frame is molded of plastic material, and the bottom panels are sheets of cardboard.

10 End members 3 and side members 5 are generally of angle shape in cross section throughout their lengths, and the central member 7 is generally T-shaped in cross section throughout its length. The arrangement is such that the end members 3, and side members 5 have flange portions 10 and 11, respectively, directed inwardly in the plane of the frame to form a flange around the inside of the frame. The central member 7 has oppositely directed flange portions 13 which lie in the plane of and form extensions of the above flange portions 10 and 11. Extending perpendicularly to the plane of the frame are wall portions 15 and 17 formed on the end and side members, respectively, and a stem portion 19 formed on the central T-shaped member 7. In effect, the frame 1 consists of two smaller rectangular frames with inwardly directed flanges.

15 The bottom panels 9 are of such rectangular outline as to fit within the walls 15, 17, 19 and lie marginally beneath the flanges 10, 11, 13. The margins of the panels abut the lower edges of a plurality of partitions 21 spaced along the bottom sides of the flanges 10 and flanges 13 at the ends 3 and center 7 of the frame. The partitions 21 are narrow bosses formed integral with the frame extending lengthwise thereof projecting slightly from beneath the end flanges 10 and central flanges 13. They lie in planes generally at right angles to frame members 3 and 7 and to the plane of flanges 10 and 13. The partitions on the end members are opposed to the partitions on the central member, and are equidistantly spaced apart to provide pockets 23 of width corresponding to the width of the cards.

20 The bottom panels 9 also abut against a plurality of bosses 25 on the bottom sides of flanges 11 at sides 5 of the frame. Bosses 25 extend lengthwise of the frame at the inner edges of the flanges, and serve the dual purpose of holding the bottom panels 9 spaced from the side flanges 11 and preventing the cards from slipping under these side flanges.

25 A plurality of inwardly projecting lugs 27 and 29 at the back of the frame abut the rear faces of backing panels 9. Lugs 27 are formed integral with wall portions 15 at the ends 3 of the frame, and lugs 29 are on the wall portions 17 at the

sides 5 of the frame. Thus, the bosses 25 and lugs 29 at the sides of the frame, and the partitions 21 and lugs 27 at the ends of the frame define channels along three sides of each half of the frame for receiving a bottom panel 9. The panels are inserted endwise from the center of the frame, and are secured in place by a removable backing member 31, which is fastened by screws 32 to the stem portion 19 of the T-shaped central member 7.

The bands or bracelets B or the like to be displayed in the tray are fixed on the cards 33, which are of long narrow rectangular form and made of cardboard or the like. The cards are adapted to be inserted at their ends 35 into the pockets 23 formed at the center and ends of the tray by partitions 21 in conjunction with flanges 10 and 13 and bottom panels 9. For example, a band B is tied on a card 33 as shown in dotted lines in Fig. 1, and the ends 35 of the card are caught beneath the end and center flanges 10 and 13, respectively. At the ends of the frame under the flanges are stops 39 adapted to cooperate with the ends 35 of cards 33. The cards 33 are of a width corresponding to the spacing of the partitions 21.

It will be observed that the cards 33 rest upon the bottom panels 9 and are held in the tray by the end and center flanges 10 and 13, respectively. Sidewise movement of the display cards is prevented by the partitions 21 and bosses 25. The tray is adapted to carry a plurality of the display cards 33 and thereby a plurality of items B. For example, the tray illustrated carries ten such items. When an item B is sold, it is removed together with the display card to which it is attached. The flexibility of the display cards permit removal. As various items are sold, new display cards may be placed in the tray. Also, the backing panels 9 may be readily replaced if they should become damaged.

It will be noted that certain of the rear lugs 27 and 29 have feet 41 formed inwardly and projecting rearwardly from the tray. These feet are adapted to cooperate with the top of another frame so that several trays may be readily stacked. A top molding is provided at 43 for cooperation with such feet.

In view of the above, it will be seen that the several objects of the invention are achieved and other advantageous results attained.

As many changes could be made in the above constructions without departing from the scope of the invention, it is intended that all matter contained in the above description or shown in the accompanying drawing be interpreted as illustrative and not in a limiting sense.

I claim:

1. A tray for displaying watch bands, bracelets or the like that are mounted on narrow flexible display cards, comprising an open rectangular frame having two opposite frame members spaced apart the length of said display cards, inwardly directed flanges on said opposite frame members, opposed transverse partitions on the bottom sides of said flanges in planes generally at right angles to said opposite frame members and to the planes of said flanges and spaced apart the width of said display cards, a bottom panel of lightweight sheet material fitted in the frame, one face of the bottom panel abutting the partitions, and inwardly projecting members on said frame abutting the other face of the bottom panel and holding it in the frame.

2. A tray for displaying watch bands, bracelets or the like that are mounted on narrow flexible

display cards, comprising an open rectangular frame of molded plastic having two opposite frame members spaced apart the length of said display cards, inwardly directed flanges formed on said opposite frame members, opposed transverse partitions formed on the bottom sides of said flanges in planes generally at right angles to said opposite frame members and to the planes of said flanges and spaced apart the width of said display cards, a sheet of cardboard fitted in the frame forming a bottom panel, one face of cardboard sheet abutting the partitions, and inwardly projecting members on said frame abutting the other face of said cardboard sheet and holding it in the frame.

3. A tray for displaying watch bands, bracelets or the like that are mounted on narrow flexible display cards, comprising an open rectangular frame having an inwardly directed flange, opposed transverse partitions formed beneath the flange at opposite ends of the frame in planes generally at right angles to said ends of the frame and to the plane of said flange, bosses formed beneath the flange at the other sides of the frame,

20 25 a sheet of cardboard fitted within said frame, one face of the sheet marginally abutting said partitions and bosses, and inwardly projecting lugs on said frame abutting the other face of said cardboard sheet and holding it in the frame.

30 35 40 4. A tray for displaying watch bands, bracelets or the like that are mounted on narrow flexible display cards, comprising a molded plastic open rectangular frame having an inwardly directed flange, narrow partitions formed beneath the flange at opposite ends of the frame in planes generally at right angles to said ends of the frame and to the plane of said flange, bosses formed beneath the flange at the other sides of the frame, a sheet of cardboard fitted within the frame, one face of the sheet marginally abutting said partitions and bosses, and inwardly projecting lugs on said frame abutting the other face of said cardboard sheet and holding it in the frame.

45 5. A tray for displaying watch bands, bracelets or the like that are mounted on narrow flexible display cards, comprising an open rectangular frame having end members spaced apart a distance corresponding to twice the length of the display cards and a central dividing member, inwardly directed flanges on the end members and

50 55 60 65 oppositely directed coplanar flanges on the central member, opposed transverse partitions formed beneath said flanges in planes generally at right angles to said end members and central member and to the plane of said flanges, bosses at the sides of the frame, rectangular panels of cardboard fitted within said frame on opposite sides of the central member, the front faces of the panels marginally abutting said partitions and bosses, inwardly projecting lugs on said frame abutting the rear faces of said panels for holding them in the frame, and a detachable strip on the back of said central member abutting the rear faces of said panels.
